UNITED STATES PATENT OFFICE.

ROBERT DE LAMBERT, OF MILL VALLEY, CALIFORNIA.

GAME APPARATUS.

Application filed October 16, 1923. Serial No. 668,857.

To all whom it may concern:

Be it known that I, ROBERT DE LAMBERT, a citizen of the United States, residing at Mill Valley, in the county of Marin and 5 State of California, have invented certain new and useful Improvements in Game Apparatus, of which the following is a specification.

My invention relates to mechanical field 10 games and more particularly to football games, and the invention consists of a mechanically operated device adapted to be placed upon a table or other convenient support and operated from both ends by two 15 opponents operating keyboards respectively, the keys of which in turn operating ball-projecting devices.

The invention broadly includes, a field, 20 two oppositely disposed keyboards, and two sets of different colored ball-projecting devices representing football players arranged in the field like two contesting teams, each 25 team being connected to its respective keyboard. Each set of said ball-projecting devices is provided with panels numbered from 1 to 11 connecting with keys likewise numbered. The panels represent the football players of the game.

To start the game, the ball is placed in the 30 center of the field and one of the opponents at his end of the field operates key numbered 2, thereby projecting the ball from the center of the field toward his opponent's goal, and his opponent anticipates the spot where 5 the ball may land on the field, and strikes a key on his keyboard to operate the panel or player that will halt the ball, ward it from the goal or project it toward his opponent's goal or through it, and thus score 10 a point in the game.

Therefore, briefly describing the character 5 of the game as above, one of the objects of this invention is to construct a game apparatus that will be simple in construction and operation and hence durable. Another object is the provision of a game that will be as interesting to onlookers as to the players themselves. Another object is to 10 construct a game which requires a certain amount of skill in the operation of the keyboards, thus bringing the mental faculties into play for judging which projectors may keep the ball in the field and away from his opponent's goal. A further object is to 15 construct a game of the class described pro-

vided with an enclosed field which is preferably concave transversely thereof, so that the ball will not roll off or away from the field of action but always toward it, and thus, the ball will always be in a position adapted 60 to be engaged by the projectors.

Other objects and advantages and the features of construction of the invention, will appear in the subjoined description of the accompanying two sheets of drawings, in 65 which:

Figure 1 is a plan of my game showing the field, oppositely disposed keyboards at the ends thereof, and projectors in the field in normal position ready for engagement with 70 the ball; the latter is shown in the center of the field from which spot the game is started.

Fig. 2 is a bottom plan of Fig. 1 showing the cords and general construction and 75 operating means of the device.

Fig. 3 is a perspective view on a reduced scale of one end of the field showing a modified form of end zone. The zone being an 80 enclosure having pockets to receive the ball as it passes through the goal.

Fig. 4 is an end elevation of Fig. 1 showing 85 one end of the field and one of the keyboards.

Fig. 5 is a side elevation of Fig. 1 showing the ball in action and an opponent striking a key anticipated to cause interference as the ball lands.

Fig. 6 is an enlarged plan of a portion of 90 the keyboard.

Fig. 7 is a sectional elevation taken upon the line 7—7 of Fig. 6.

Fig. 8 is an enlarged plan of one of the key stampings.

Fig. 9 is an enlarged detail plan of one 95 of the projectors.

Fig. 10 is a vertical section taken upon the line 10—10 of Fig. 9.

Referring to the drawings in detail and more particularly to Fig. 1, 1 in a general 100 way designates a frame preferably constructed of wood and preferably rectangular in shape. Said frame is adapted to rest upon a table or other support, and has a longitudinally extending concave plate 2 105 preferably of sheet metal securely nailed or otherwise fastened or formed to the top of the frame 1, thereby forming a field 2a. The corners of frame 1 are provided with clips 3, 4, 5 and 6 for the reception of wire 110

posts or uprights 7, 8, 9 and 10, which form cornerposts for supporting a fencing or netting 11 or the like, and which extends around these corner-posts and forms an enclosure for the field 2^a. Said fencing is preferably of wire strand formation, and is high enough to prevent the ball from jumping off the field 2^a.

The fencing 11 is provided with end openings 18 and 19 above the keyboards 12 and 13 respectively. Said openings are formed by inverted U-shaped wires 20 and 21 which form the goals at opposite ends of the field 2^a.

Keyboard mechanisms 12 and 13 are attached to opposite ends 14 and 15 of the rectangular frame 1. Said keyboard is somewhat like that of a typewriter keyboard, and the keys thereof are numbered from 1 to 11. Number 1 key is positioned in the center and the even numbered keys are on one side thereof and the uneven on the other side as shown to advantage in Fig. 1. The number (1) key, 16 for instance, is centrally located as above stated and is connected to the nearest projector element 17, which is wider than the other projectors in order to block the goal.

The keys of the keyboard mechanism 12 are connected individually with half of the projectors in the field 2^a. Said keys are correspondingly colored and numbered to match the projectors or team to which they are attached, so that the operator will be able to distinguish his men or projectors on the field.

The keys upon the keyboard 12 are numbered from 1 to 11 as above stated, and the corresponding projectors to which they are attached are also numbered accordingly. As the operation of all the keys and connections therefrom to the projectors are similar, I will therefore describe but one complete key unit which will answer for all of them.

Referring to the detailed Figs. 6 and 7 the key mechanism 12 is shown as the keys appear in normal position. The key 16 is shown partially in section in Fig. 7 and is hingedly connected at 22 by the pintle 23 to the end plate 24 fastened to the end piece 14 of the frame 1. The pintle 23 extends from one end of the keyboard 12 to the other, and hingedly connects all of the keys of the keyboard 12 to the end plate 24. The key 16^a is shown in detail in Fig. 8 previous to bending and comprises a stamping of one piece of metal and is adapted to extend upwardly as indicated at 24^a from the pintle 23 and is bent outwardly at right angles as indicated at 25, terminating in a cupped finger-rest 26. A series of U-shaped guide clips 27 shown clearly in Fig. 6, are placed between the keys and fastened to the plate 24 by rivets or the like 28. These

clips are adapted to guide the movement of said keys.

A wire or other flexible connector 29 extends through an opening 30 in the end plate 24, and is secured to the upwardly extending portion 24^a of said key 16, and an opening 31 is formed in the end piece 14 so that said flexible connector 29 may operate freely therethrough. The other end of said connector is attached to the lower end or shank of the projector 17 as at 17^a Fig. 10, and may pass through screw eyes 33 or the like, Fig. 2, for guiding and non-interference purposes of the connectors 29 leading to their respective panel members 17^a. Number 2 key is connected in a similar manner with the projector numbered 2, and number 3 key is connected in the same manner with the projector numbered 3, and remaining keys are similarly connected with their respective projectors.

Referring to Figs. 9 and 10, one of the projectors and means for operating same is shown in its normal position upon the plate 2. Said projector preferably consists of a flat piece of sheet metal stamped out substantially in the form of a T. Ears 32 are formed upon the shank 33 thereof, and the said shank is perforated at its lower end for the pivotal securing thereto of one of the aforesaid flexible connectors 29. Openings 34 are punched in the plate 2, the punched metal thereof forming downwardly extending ears 35; said ears 35 and the ears 32 formed upon the shank 33 are perforated in alignment for the reception of a pin 36. A piece of clock-spring or the like 37 is positioned below the plate 2 and over the pin 36 and is crimped under the shank 33 for securing thereto; the reaction of said spring causes the panel 38 of the projector to assume its normal position down against the plate 2 after each key action. Thus, when one of the keys of the keyboard 12 is pressed downwardly as shown in Fig. 5 the connector 29 pulls outwardly thereby swinging the projector 17 upon the pin 36 to a nearly vertical position. If the ball 39 be placed upon the plate 2 in front of the panel 38 and the key operated as above stated, the ball will be projected forwardly from said panel and the projector will return to its normal position immediately upon release of said key. The action of the ball is proportional to the finger-pressure applied to the key.

Referring to Fig. 5 I have shown in side elevation the clip 3 with the corner-post 7 in place therein. Said clip consisting of a piece of metal bent to form a rectangular housing 40. Said housing having an opening 41 formed in one wall thereof. The corner-post 7 extends downwardly into the housing 40 and has the lower end thereof

recurved as indicated at 42, thence outwardly and forming a pintle 43 for engagement with said opening 41 of the clip 3. When it is desired to remove said corner post, the pintle 43 is pressed inwardly out of engagement with the opening 41, and an upward pull of the spring wire post releases it from the previous binding engagement within the clip.

10 The under side of the frame 1 is provided with corner buffers or the like 44, 45, 46 and 47 preferably constructed of soft rubber or some resilient material. Said buffers are attached to the corners of the frame to protect the table or other support upon which the frame is placed.

20 Fig. 3 illustrates a different form of end construction, and consists of an added end zone enclosure 48, for the checking of the ball as it passes through the end goal 18, directing the ball into one or the other of the sloping side pockets 50 and 51. The said slope begins at the longitudinal center line of the plate 2 as at 52. The only difference in this construction is that I have provided a retarding and receiving means for the ball, instead of allowing it to pass on through the goal and perhaps to the floor.

25 Fig. 1 shows the ball in position to start the game, and when the said ball is projected toward either end of the field 2^a, the operator at the end toward which the ball is projected will endeavor to operate the proper key and panel to stop said ball and return it toward his opponent's goal and through it, and so on.

30 It is obvious from the foregoing that I have endeavored to produce a mechanical game intended to imitate as nearly as possible a football game, that is, I have constructed a field of the character described having projectors to represent two opposing teams, and it is my object to have the 40 opposing players imitate the movement of the players in a football game. The main object being for the players to get the ball from their end of the field to the opposite end and through the goal in order to score 45 points.

50 The plate 2 is concave transversely thereof so that the lowest part of the field lies longitudinally, so that the ball will have a tendency to return to this area and be always in place to be engaged by a projector, the latter being so spaced and the ball of such diameter that it will always be in the range of action of a projector.

55 It will be seen from the foregoing description that I have produced a mechanical game for grown people as well as for children, and is intended to develop skill in anticipating the next move of the opposing side and quick action on the part of the 60 players to keep the ball in motion.

Having thus illustrated and described my invention in its preferred form, I wish it understood that the same may be modified as practice suggests. Therefore, the patent protection that I desire, is all of that which 70 comes within the spirit and scope of the invention as claimed.

I claim:

1. A football game apparatus comprising a frame, a plate mounted longitudinally in said frame and its entire surface concaved transversely thereof to form a field, said plate having a series of oppositely arranged superposed ball projectors hingedly mounted thereon, keyboard mechanisms mounted 75 at opposite ends of said frame and means connecting said keyboards and projectors to raise and lower said projectors upon the operation of the keys of said keyboards, the keys being manually operable and 80 spring returnable.

2. A game apparatus comprising a frame, a plate upon said frame, oppositely disposed sets of T-shaped ball projectors hingedly mounted in said plate to the underside 90 thereof, a spring interposed between the hinge pin and the shank of the T-projector, keyboard mechanisms and means connecting said keyboard mechanisms with respective sets of ball projectors, so that upon the depression of the keys said projectors will be 95 swung forwardly upon their hinges, and upon the release of said keys said projectors will immediately return to normal position 100 by the reaction of said spring.

3. A game apparatus comprising a framing including a plate, a series of spring-actuated sheet-metal ball projectors hingedly mounted in said plate and adapted to normally rest thereupon, a series of actuating keys mounted upon said framing having wire connectors to said projectors, so that when the keys are depressed the projectors will be raised against the actuating springs and when released will return to 105 normal position.

4. A game apparatus comprising a framing including a plate, a series of projectors hingedly mounted in said plate and adapted to normally rest thereupon, actuating means 110 for said projectors, the latter being stamped from sheet metal and having ball-engaging panels at their upper ends and shanks extending downwardly therefrom and connected with said actuating means to raise 115 and lower said panels.

5. In a ball game apparatus, a framing, goals near the opposite ends of the framing, and zone enclosures at the said opposite ends adjacent said goals, each of the said 120 zones provided with a plurality of pockets for the reception of the ball after a goal-point is scored.

6. A field game comprising a framing having a longitudinally concave top sur- 130

rounded by a fencing, projectors spaced and pivotally fixed on said top in predetermined positions to represent two contesting teams, each team of said projectors being of a different color for designation, and a keyboard fixed to each end of said framing having each key thereof operably connected to

a different projector, and each of said keyboards adapted to be operated upon to selectively control any projector on its respective team. 10

In testimony whereof I affix my signature.

ROBERT DE LAMBERT.
